AUTOMATIC ARM.

Application filed October 5, 1925, Serial No. 60,661, and in Germany October 6, 1924.

Our invention relates to automatic arms, having a barrel arranged for short recoil, which recoil movement is transmitted to the breech bolt and involves an improved transmission of the recoil momentum of the barrel to the breech bolt, then an increased delay in the opening of the bolt and means for dislodging the spent shell by means of a front blow.

10 To these ends we employ a special lever mechanism, then specially formed governing working surfaces of the main parts of the breech bolt, and finally we determine the weight of the moving and stationary parts 15 according to certain useful proportions.

In the accompanying drawings

Fig. 1 is a central longitudinal section in the vertical plane, showing the bolt in its closed position.

20 Fig. 2 is a longitudinal section of the mechanism, showing the slide retired to the beginning of the unlocking movement.

Fig. 3 is the same longitudinal section, showing the bolt open.

25 Fig. 4 is a frontal view of the lever mechanism.

Fig. 5 is a cross section through the bolt.

Fig. 6 shows the working surfaces of the slide.

30 Fig. 7 is a lateral view of another form of the lever mechanism.

Fig. 8 shows the working surfaces of the slide with slowly increasing elevation. The corresponding surfaces of the bolt 5 are 35 drawn with dotted lines.

Fig. 9 shows our invention as applied to a block bolt and with an unlocking lever.

Fig. 10 shows the same mechanism, but without an unlocking lever.

40 The mechanism consists of a barrel 1 to which a recoil movement of about $\frac{3}{8}$ - $\frac{1}{2}$ inch, in the case, is allowed. The spring 4 holds the barrel 1 in its foremost position and returns it thereto after each recoil movement.

45 The positively locked breech bolt, which is of the straight pull type, consists, as usual, of two main parts, the bolt 5 which supports the bottom of the shell and a slide 7 which 50 operates the bolt.

The bolt is shown in Figs. 1-8 as a turning bolt but any other bolt system (block or locking lever bolt etc.), can be chosen.

55 In the form of the invention as shown in Figs. 1-8, the slide 7 is situated below the

bolt 5. It can, as a matter of course, be placed on any other side of it, or in it, or around it.

This slide 7 carries working surfaces, of which the one opens the bolt, the other 60 closes it.

The opening surface 9 is shaped as a long drawn curve, rising at first, but slightly, and farther on more rapidly. (See Fig. 8). Thus, in the first phase of the backward movement of the slide 7 but a small fraction of the unlocking movement of the bolt is performed, the balance of it being done by the farther, more steeply inclined part of the surface 9.

65 If the recoil movement of the slide 7 must in its first phase be further facilitated, then the elevation of the foremost part of the opening surface 9 of the slide 7 can be reduced to zero, so that in that case the opening surface 9 consists of a straight part and of a curved one (Fig. 6). It then allows to the slide 7 a free movement, within which it does not engage or influence the bolt 5.

70 The two main parts of the bolt can be 80 made to engage one another by means of grooves and threads, or of lugs, or of an arm, or in any other way.

75 The slide 7 is supported by a closing spring 12^a, by which the forward movement 85 of the breech bolt is effected.

The firing mechanism can be freely chosen and constructed.

Between the barrel 1 and the slide 7, a main lever (26, 30) is inserted (Figs. 1, 2, 3, 4 and 7). This main lever can equally well be situated either on the barrel, or on the case, or on the slide, or on the bolt. It causes the barrel to transmit to the slide 7 the greatest part of its recoil momentum. For this purpose the main lever 26, 30 is so formed and so arranged that it accompanies the recoiling barrel in the first phase of its movement without working, so that its accelerating effect upon the slide only makes itself felt in 90 the last phase of the recoil movement of the barrel 1.

95 Whenever the main lever is pivoted on the barrel 1, or on one of the main parts of the breech bolt, the projection 29 of the case 2 which engages the short arm 28 of the main lever is placed some distance ahead of this short arm, so that this arm only can hit it in the last stage of the backward travel of the barrel. Thus the main lever only can acceler- 100 105 110

ate the slide 7 in this late phase of the movement of the barrel.

In such case, when the main lever 30 is pivoted on the case 3 as shown in Fig. 7, we 5 construct it in such a way that its back is curved and so formed that the farthest end of the lever touches the corresponding operating surface 31, which can be situated either on the barrel 1 or on the bolt 5. Accordingly, during the first stage of the recoil movement of the barrel almost no acceleration of the slide 7 takes place. Now, 15 during the continued rotation of the main lever 30 its point of contact with this operating surface 31 shifts towards the axis of the main lever 30, the leverage increases and so the accelerating effect of the main lever 30 is delayed in this case also, so that it only takes place in the last period of the recoil 20 movement of the barrel.

Generally a catch 15 is situated in the case, the object of which catch is described later on.

Figs. 9 and 10 show our invention adapted 25 for a bolt of the block system.

According to the construction shown in Fig. 9 an unlocking lever R is situated in the block bolt 5 and the slide 7 is provided at its rear end with a surface 8, by which 30 the closing and locking of the bolt 5 is effected, and with a simple lug 12 placed at a certain distance from the lower arm of the unlocking lever R in order to insert a free movement between the two main parts of the 35 breech bolt. The relative situation of the parts of the breech bolt at the end of the unlocking movement is shown by dotted lines.

With the mechanism shown in Fig. 10, the 40 locking and unlocking of the bolt 5 is done by means of an arm of the slide 7 which projects into a recess T of the bolt 5. This arm of the recoiling slide strikes against the surface 12 of the recess T, forcing the bolt 5 45 downwards and so unlocking the latter from the case 2.

The length of the free movement of the main parts of the breech bolt is controlled by the length of the recess T.

From this description it is seen, that barrel, slide and bolt recoil at first together, 50 without any change in their relative positions. In a later phase of the movement of the barrel the main lever 26, 30 begins to 55 work and increases the recoil velocity of the slide 7. This slide leaves then the barrel and recoils alone. The barrel and the bolt 5 have, in the meantime, finished their backward movement, they stand still and then 60 begin to move forward, the bolt 5 still being firmly locked with the barrel. After some 1½-3 inches of recoil movement of the slide 7, during which it did not yet unlock the bolt, the surface 9 of the slide gets engaged 65 with the corresponding surface of the bolt

and only now, long after the barrel has absolved its recoil movement and after the main lever 26, 30 has displayed its accelerating effect, does the slide 7 open and reject the bolt 5. The bolt 5 being uncontrolled 70 by any closing spring, recoils freely and extracts and ejects the empty shell.

So the main lever 26, 30 does not work on the bolt, but on the slide which thus receives and accumulates the recoil momentum of the 75 barrel and utilizes it in a later moment, for operating the bolt 5.

It is also seen that the transmission of the recoil energy of the barrel to the slide, then the opening of the bolt by the slide both are 80 performed in different moments and by means of semielastic shocks. In order to make the best use of these shocks, certain correct proportions must exist between the masses of the barrel, of the slide and of the bolt, as well as of the weight of the whole arm or else the breech bolt would not work correctly. If these proportions be correctly chosen, then the bolt 5 generally arrives in 85 good time at its rearmost position in order to avoid being prematurely driven forward by the returning slide. In such cases, when a belated arrival of the bolt 5 in its rearmost position is inevitable, we employ a catch 15 which catches the returning slide 7 and retains it until the recoiling bolt 5 depresses the nose 18 of the catch 15 and with it the catch 15 itself and thus releases the slide 7. Then the breech bolt is closed by the main 90 spring 12a.

The catch 15 can serve as interruptor also, 95 port by its forearm 16 the slide 7 in its 24 in a manner that, when depressed, it shifts the link 23 forward, until it releases the sear 24 which can then correctly re-engage the 100 hammer.

The catch 15 can well be employed to support by its forearm 16 and slide 7 in its 105 foremost position. In this case, the catch 15 can be made use of as a safety device which prevents premature firing of the arm, because it only releases the link 23 of the sear, in its uppermost position that is, when the bolt is completely closed.

Another useful feature of the breech bolt 110 mechanism we have described is the fact that the very economical utilization and gradual transmission of the recoil momentum of the moving parts results in a weak and very elastic recoil of the entire arm, more so indeed, than is the case with most other automatic arms. Consequently we can make 115 arms of very light weight, or shoot more powerful cartridges from rifles of the usual 120 weights.

Having now particularly described and ascertained the nature of our said invention and in what manner the same is to be performed, we declare that what we claim is:

1. In an automatic fire arm having a barrel 125

- arranged for short recoil and a bolt, the combination with the barrel of a bolt actuating slide and a lever to actuate the slide, the lever being adapted to receive and to transmit to the slide the impact of the recoiling barrel, the slide being adapted to open the bolt by its own impact, said barrel being arranged for lost motion equal to more than two thirds of the total recoil movement thereof before the slide is actuated by the lever, and said slide being arranged for lost motion equal to more than twice the total recoil movement of the barrel, before the bolt is actuated by the slide.
2. An automatic fire arm as claimed in claim 1, in which the operating surface of the slide by which it effects the opening of the bolt ends in a recess by which the unlocking movement of the bolt is positively limited and the opening of the bolt is effected by a blow.
3. An automatic fire arm, as claimed in claim 1, in which the slide has a closing surface, inclining at an angle which is greater than the angle of the opening surface.
4. An automatic fire arm, as claimed in claim 1, in which the weight of the slide is $1/5-1/3$ of that of the barrel, or at least $1/10$ of that of the total weight of the arm and the weight of the bolt is $1/1.5-1/4$ of that of the slide thus providing proportions on which directly depends the functioning of the bolt mechanism.
5. An automatic fire arm, as claimed in claim 1, including a catch, pivoted in the case and having a hose which engages the slide when in its rearmost position and retains it until the recoiling bolt presses the catch out of engagement with the slide.

In witness whereof we affix our signatures.

JOSEF LOVÁSZ.
